SEDIMENT COLLECTING ARRANGEMENT

Kenneth O. Sisson, Dayton, Ohio, assignor to General Motors Corporation, Detroit, Mich., a corporation of Delaware

Filed June 30, 1958, Ser. No. 745,602

2 Claims. (Cl. 68—23)

This invention relates to domestic appliances and more particularly to washing machines having an improved sediment removal arrangement.

In the domestic clothes washing art it is conventional practice to wash clothes within a receptacle by means of an agitator which reciprocates or oscillates therein to loosen and remove the soil and sediment from the clothing being washed. At the conclusion of such an agitation or washing cycle, the water is removed from the tub and the clothes are damp-dried by spinning the tub in a centrifuging operation. The heavier sediment and dirt particles, during the agitation process, do not remain suspended in the washing solution and consequently, drop to the bottom of the washing tub. Thus, at the start of the spin cycle much of the sediment which has collected on the tub bottom is not carried off by the centrifuged water and remains in contact with the clothes in a manner to detract from the results of the washing process. This invention is directed to collecting this sediment during the washing or agitating process in a chamber remote from the washing tub and periodically removing the sediment in response to the opening of a valve centrifugally actuated during the spinning or centrifuging process.

Accordingly, it is an object of this invention to provide a centrifugally actuated sediment collector for a clothes washer.

It is a further object of this invention to provide a simplified sediment collecting pan which may be easily assembled on a slightly modified production spin tub.

It is also an object of this invention to form the bottom of a spin tub with ribs interposed between extruded holes to facilitate the directing of the sediment to the collecting chamber.

It is a more particular object of this invention to provide a sediment collecting chamber which is connected to the spin tub solely at the rotating support hub for the tub.

A more particular object is the inclusion of a centrifugally actuated sediment trap valve which serves to isolate the sediment collecting chamber wall from the spin tub bottom and also to regulate the flow of sediment through this wall.

Further objects and advantages of the present invention will be apparent from the following description, reference being had to the accompanying drawings wherein a preferred embodiment of the present invention is clearly shown.

In the drawings:

Figure 1 is a fragmentary sectional view of a washing machine provided with this invention;

Figure 2 is a fragmentary sectional view taken along line 2—2 of Figure 1 illustrating a production spin tub bottom modified for use with this invention;

Figure 3 is a sectional view taken along line 3—3 of Figure 2 showing the sediment trap valve in a closed position; and

2

Figure 4 is a similar view showing the sediment trap valve in a centrifugally opened position.

In accordance with this invention, a washing machine 10 of the type shown in the patent to Sisson, 2,758,685, issued August 14, 1956, is provided with a spin tub 12 and an agitator 14. An agitating and spinning mechanism, shown generally at 16 and more particularly described in the Sisson patent, is effective to vertically reciprocate the agitator 14 during the agitate portion 10 of the washing cycle and to rotate the tube 12 during the centrifuging or spinning portion of the washing cycle. An inner water container 18 collects the water spun from tub 12 during the spinning process and directs it to a drain, in accordance with the teachings of the aforementioned patent.

The tub 12 is formed with a ballast ring 20 which may be filled with any weighted material 22 such as lead or iron ore to stabilize the spinning operation of the tub. A plurality of ports 24 are formed along an upper portion of the tub 12 as a passageway for water being centrifuged from the tub during the spinning operation. An enlarged top loading opening 26 serves as the means whereby clothes may be placed within the tub 12 at the beginning of the washing procedure. The tub 12 is formed in a dished-out manner to form an annular, slightly tapered sidewall 28 and a bottom wall 30 which slopes gently in a radially inner direction toward the center support section 31 of the tub bottom. A plurality of ports 32 are formed on the tub bottom 30 and interspersed by a series of circumferentially arranged ribs 33. Underlying the ports 32 is a sediment chamber, shown generally at 34. During the agitation process, heavy dirt particles dislodged from the clothing by the reciprocating action of agitator 14 fall by gravity to the bottom 30 of the tub 12. The movement of the water or liquid within the tub and the sloping configuration of the tub bottom 30 and the ribs 34 direct the sediment through the ports 32 into the sediment chamber 34 where the unwanted material remains during the balance of the agitation cycle as determined by a conventional washing machine timer (not shown). The agitating and spin mechanism 16 is next energized to initiate a spin cycle wherein an annular sediment trap valve, shown generally at 36, is opened by centrifugal force to pass the sediment collected through a series of circumferentially arranged ports 37. Upon termination of the rotation or spinning of the tub 12, the valve 36 automatically reseats itself into liquid retaining engagement with the sediment outflow ports 37.

A more particular description of the configuration and assembly of the novel sediment trap 34 will be clearly set forth in connection with Figures 2, 3 and 4. Figure 2 may be referred to as illustrative of a fragmentary portion of a spin tub modified in accordance with the concepts of this invention. Since the application of a sediment trap is an added cost item and serves as a feature on the higher priced models of a complete washing machine line, it is desirable to effect as much interchangeability of parts as is possible. For this reason, the tub 12 without the collecting ports 32 is such that it serves in other models of a washing machine line not provided with the sediment removal arrangement of this invention. To modify a production tub for use with the sediment trap or chamber 34, the tub bottom 30 is formed with a plurality of holes 32 spaced somewhat from the side wall 28 of the tub toward the center of the bottom and adjacent the tub support section 31. Research has shown that approximately two hundred sediment collecting holes 32, $\frac{1}{16}$ " in diameter, are effective to pass sediment which normally falls from a washing load in a 20" diameter tub without passing articles of clothing being washed. The holes 32 should be extruded slightly,

outwardly to remove the sharp edges from the inside of the tub bottom 30 and in a manner to form a tapered or depressed surface surrounding the hole as an aid in collecting the sediment. The holes 32 are arranged circumferentially about the tub bottom in circles spaced from the center of the tub bottom. Three circles of holes have been particularly effective in the application of this invention. Interposed between each group of holes 32 are ribs 33 which are raised from the tub bottom 30 in a manner to strengthen the bottom 30 and to direct sediment toward the holes 32.

The tub 12, as modified, may now be subjected to an enameling or porcelain coating process, which aids in providing a rust-free, long life for the tub structure. Therefore, when applying an appurtenance to the tub, such as a sediment trap 34, it is imperative that the porcelain coating not be chipped to form a point at which rust can invade the otherwise impervious coating. Many years of development have gone into the Figure 3 structural arrangement to acquire a satisfactory attachment of the tub 12 to the rotating support disc 38 without rupturing the porcelain coating on the tub. Experience has shown that the life expectancy of a porcelain tub is directly related to the number of rigid connections which are made through the tub wall. For these reasons, this invention is directed to a sediment trap which may be secured to the tub bottom 30 at the same point at which the tub 12 is attached to its support disc 38. In this manner, no fastening means need pass through the enameled or porcelain coated tub walls and a particularly efficient and long-lasting tub 12 is the result.

The sediment trap or chamber 34 is formed with an annular collecting pan 39 having a bottom 40, a radially inner support flange 42 and a radially outer, generally upright outflow port valve flange 44. The inner flange 42 is drilled or punched to receive fastening means 46 which also pass through the tub bottom 30 and the support disc 38 to effect a secure, sandwiched relationship of the parts. Suitable resilient seals to guard against vibration and moisture leakage are effected through cork discs or washers 48 interposed between the metal parts in the sandwiched relationship secured by the fastening means 46. The outer flange 44 is formed with a plurality of outflow ports 37 as by a stamping process prior to the drawing operation which forms the collecting pan into the configuration of sediment chamber 34 shown in the drawings. These outflow ports have been formed $7/16$ " in diameter and sixty-four of such equally spaced peripherally arranged ports 37 have been found effective to eliminate all of the sediment which collects in the chamber 34 during a clothes agitation cycle. The collecting chamber 34 must be so formed that the tub bottom or sediment collecting ports 32 overlie the chamber 34 in a manner to direct all of the sediment falling to the tub bottom 30 to the collecting chamber.

For effectively controlling the passage of sediment through the ports 37, isolating the collecting pan flange 44 from the tub bottom 30 and preventing leakage from the tub 12 and the sediment chamber 34 during agitation, a novel configuration has been provided for the annular sediment port valve 36. The valve 36 is formed with a tub bottom seal portion 50 and an outflow port seal or port valve portion 52. A relatively thin neck portion 54 separates the tub bottom seal portion 50 and the outflow port seal portion 52 to permit a measure of flexing or hinging for the port seal portion 52. The annular seal 36 is formed of any suitable resilient material which has effective water-sealing characteristics and is sufficiently flexible to permit the port valve end 52 of the seal to flex outwardly during spin. As an aid to the return of the valve portion 52 into moisture-sealing relationship with the sediment trap flange 44, a garter spring 56 is enclosed within the port seal portion 52. The seal 36, of course, may be formed with a slot

for admitting the spring 56 in an operation subsequent to the extrusion thereof or the spring may be merely vulcanized into the seal. To further improve the sealing characteristics around the points at which water would be most likely to pass, a labyrinth arrangement 58 is formed on the face of the port seal portion 52, and a labyrinth 60 on the tub bottom seal portion 50. As a further aid in economy of production and speed of assembly, the seal 36 is formed with a slot 62 which is adapted to receive the upper end of the collecting pan flange 44. Thus, the seal 36 may be quickly attached to the flange 44 of the sediment pan and thereby correctly placed with reference to both the tub bottom 30 and the outflow ports 37. The tub seal portion 50 serves also to compensate for any dimensional variations due to a mal-formed tub bottom 30 which are encountered in assembling the collecting pan 39 to the tub bottom 30.

In operation, the clothes to be washed are placed within the tub 12 through the opening 26 and a washing cycle initiated by any conventional timer means (not shown). During the washing portion of the cycle the agitator 14 will be reciprocated vertically by the agitating and spinning mechanism 16 in a manner to loosen the soil and sediment from the clothing. Grease and certain other soluble substances will remain in the washing solution and will be passed out with that solution during the subsequent spinning operation. However, certain heavier sediment such as sand, will fall to the bottom 30 of the tub 12 as it becomes dislodged from the clothing. The action of the sloped surfaced ribs 33 will direct this sediment to one of the many holes 32 through which the sediment may fall into the collecting chamber 34. The liquid within the chamber 34 is relatively calm compared to the liquid within the tub 12 and thus the sediment remains therein during the balance of the agitation process. At the conclusion of the agitation the mechanism 16 is controlled to initiate a spinning operation of the tub 12. As the tub rotates faster, the liquid within the tub is spun or centrifuged from the tub through the upper ports 24. Simultaneously therewith, the spinning action of the tub will impart a centrifugal force to the port seal portion 52 of the annular seal 36 and the valve will assume a position such as that shown in Fig. 4. At this point the sediment collected within the chamber 34, along with the water lying therein, will be thrown centrifugally through the ports 37, the water serving to purge the chamber. During the spinning operation the portion 52 of seal 36 remains expanded along with the enclosed spring 56. Thus, as the rotation slows to a stop, the combined resilience of the expanded portion 52 and spring 56 will serve to return the portion 52 to the port flange 44. It is important that an effective seal be maintained when the port seal portion 52 returns to prevent water leakage from the tub 12. The novel configuration of the applicant's seal has been found particularly efficient in this regard.

In view of the construction outlined hereinabove, it should be apparent that the applicant has contributed an improved sediment trap which may be simply and quickly attached to a modified production washing machine tub to provide an effective removal of sediment settling out of the washing solution.

While the embodiment of the present invention as herein disclosed constitutes a preferred form, it is to be understood that other forms might be adopted.

What is claimed is as follows:

1. In a washing machine, a liquid and sediment holding receptacle having a substantially imperforate single side wall and a bottom, an agitator in said receptacle, means for reciprocating said agitator and spinning said receptacle including a support disc for said receptacle, said side wall having a plurality of apertures about the top thereof for centrifugally passing liquid during said spinning, said bottom having a plurality of extruded holes for gravitationally passing sediment during said reciprocating and strengthening ribs for directing said sedi-

ment to said holes, an annular sediment collecting pan underlying said holes and having a continuous radially directed support flange on the radially inner side of said pan and an upstanding valve flange on the radially outer side of said pan, said valve flange having a plurality of ports in side by side relationship, means for attaching said collecting pan by said support flange only between said bottom and said support disc, an annular valve means carried by said valve flange and having a receptacle bottom seal portion and a port seal portion, a spring embedded in said port seal portion for contracting said port seal portion, said bottom seal portion having a slot for receiving said valve flange whereby said flange and said receptacle bottom are spaced in resilient water tight relationship, and said port seal portion having a spring contracted position for closing said ports during said reciprocating and an expanded position for passing said sediment during said spinning.

2. In a washing machine, a liquid and sediment holding receptacle having a side wall and a bottom, an agitator in said receptacle, means for moving said agitator and rotating said receptacle, said side wall having means for passing liquid during said rotating, said bottom having an imperforate hub portion and holes radially outwardly of said hub portion for passing sediment during said moving, a sediment collecting pan underlying said bottom and having a single support flange adjacent said hub portion, a valve flange radially outwardly of said holes and having

5
